(57) **CLAIM**

The ornamental design for a condiment kit, as shown and described.

DESCRIPTION

FIG. 1 is a top perspective view of the condiment kit showing my new design;

FIG. 2 is a right side view thereof, the left side being a mirror image; and,

FIG. 3 is a top perspective view of the condiment kit with a lid of its external container being open to show a receptacle for condiment, other receptacles shown in broken lines for illustrative purposes only and forming no part of the claimed design.
